NUT

George S. Wing, Palos Verdes Estates, Calif., assignor to
Hi-Shear Corporation, Torrance, Calif.

Filed June 22, 1970, Ser. No. 23,598

Term of patent 14 years

Int. Cl. D8—10

U.S. Cl. D8—273

FIG. 1

FIG. 2

FIG. 3

FIG. 4

FIG. 5

FIG. 1 is a side elevation showing a nut according to the invention;

FIGS. 2 and 3 are top and bottom views of FIG. 1 respectively; and

FIGS. 4 and 5 are cross-sections taken at lines 4—4 and 5—5 respectively of FIG. 1.

I claim:

The ornamental design for a nut, as shown.
